EXTENSION DOORLOCK

Filed Dec. 15, 1928

Witness:

UNITED STATES PATENT OFFICE

AUGIE L. HANSEN, OF CHICAGO, ILLINOIS, ASSIGNOR TO A. L. HANSEN MFG. CO., OF CHICAGO, ILLINOIS, A CORPORATION OF ILLINOIS

EXTENSION DOORLOCK

Application filed December 15, 1928. Serial No. 326,171.

This invention relates to improvements in extension door locks, and more particularly to locks for vehicle doors characterized by the location of the inside operating handle at a distance from the lock and preferably near the center of the door where it is more accessible to the driver or occupants of the vehicle.

The extension lock, so called, is now extensively used for pleasure vehicles, so that the novelty of the present disclosure resides not in the broad idea but rather to an improved design for such a lock, with particular consideration for the problem of the body builder or vehicle manufacturer in applying the same to the door frame. So far as I am aware, it is the present practice to manufacture this type of lock in several parts or units consisting of a lock casing, an extension inside handle mounting and a connecting member or link which must be fitted and applied separately to the door frame.

It is the object of the present invention to provide a one-piece self-contained extension lock which may be applied to a door frame as a unit, thus eliminating the additional labor of fitting, assembling and adjusting the parts as is the case in the usual design of locks of this type.

A preferred embodiment of the invention is disclosed in the accompanying drawings, in which

Figure 1 is a view in rear or inside elevation of a typical frame for a vehicle door with the extension lock applied.

Figure 2 is a view in end elevation of the door frame with the lock applied.

Figure 3 is an enlarged view in elevation of the extension lock removed from the door, and

Figure 4 is a top plan view of the lock, with the bolt casing shown in section as taken on line 4, 4 of Figure 3.

The door frame 1 to which the lock is applied consists of the usual upright frame members or stiles 2, top and bottom rails 3, 3 and an intermediate cross-member 4, the latter dividing the window opening above, from the enclosed space or well below, for the glass window panel.

For convenience, the left-hand stile will be considered the front or free edge of the door, it being understood that the hinges would be mounted along the opposite edge when the door is fitted into the door opening of the body frame. 55

Referring to the lock, the same consists generally of a rectangular base plate 5 elongated in one direction to a length somewhat less than one-half the width of the door frame. At one end of the plate is a flange 5a bent substantially at right angles. Secured to the back face of the plate 5 and immediately behind the flange 5a is a bolt casing 6 enclosing the locking bolt 7, the same being of the usual endwise shiftable type backed by a spring (not shown), the end of the bolt projecting through a slot in the flange 5a. The bolt casing 6 is relatively shallow and has a flange 6a along its rear edge, which is preferably spot-welded to the base plate. 60 Journalled in the lock-casing adjacent the lower edge of the bolt is a bushing 8 having a square axial bore to receive the square shank of the outside T-handle 9. Fixed to the bushing is a lever 10 having an arm 10a extending into a slot 7a in the adjacent edge of the bolt 7, the length of the slot being equal to the throw of the bolt. The bolt is backed by a coil spring 11, lying within a 65 channel 7b in the bolt and bearing against the end wall of the bolt casing. Thus by turning the T-handle the bolt is shifted in the usual manner to release it from its keeper (not shown) on the door jamb. Inasmuch 70 as the construction of the lock proper follows the usual practice, it has not been thought necessary to describe or illustrate it in detail. 75

Adjacent the opposite end of the base plate 90 from the bolt casing is the mounting for the inside extension operating handle 13 comprising a stub-shaft 14 passing through a hole punched in the base plate. A flanged cup-shaped boss 15 of pressed metal is welded 95 to the inside face of the plate 5, and forms an additional bearing for the stub-shaft 14. The handle 13 is fixed to the stub-shaft 14 in any suitable manner, although preferably in such a way that the handle may be re- 100

moved and shifted to any angular position on the stub-shaft for convenience of operation.

Fixed to the end of the stub-shaft 14, on the reverse or outside face of the base plate 5, is a gear sector 16 having four gear teeth. Meshing with this gear sector is a complementary sector 17 journalled on the base plate at the proper radial distance from the axis of the first sector and near the bolt casing 6. As these sectors are designed, there are three intermeshing teeth 16a and 17a, and one large or oversized tooth 16b and 17b on each sector, so that the two can rotate through say 30° in either direction, but are locked against further rotation in one direction by the locking of the two large teeth. Integral with the second or driven sector 17 is a slotted arm 18 offset slightly from the plane of the sector so that it stands away from the face of the plate and in its normal position extends lengthwise of the base plate and in line with the bolt 7. Connecting the bolt 7 with the slotted arm 18 is a rod 19, its ends being bent at right angles to form short stubs 19a, one slidably engaging the slot 18a in the arm 18, and the other inserted into a hole 20 drilled through the bolt 7 near its rear end. To reach the bolt, the rod passes through an opening 21 cut in the end wall of the bolt casing 6.

As shown in Figures 1 and 2, the complete locking device is fastened to the inside of the door frame 1 at the intersection of the front stile 2 and the cross-member 4, with the lock case 6 innermost and the inside handle 13 outermost. Along the forward and upper edges of the base plate are screw holes 5b punched and counter-sunk to receive the screws which secure the device in place. It will be noted that the front stile 2 is rabbeted along its inside edge so that the flange 5a of the base plate lies in this rabbet, and additional screws are driven endwise through screw holes at each corner of the flange. As thus mounted, the upper margin of the base overlies the lower edge of the cross-member 4 which just clears the connecting rod 19 and gear sectors 16 and 17, while the stile 50 and a portion of the cross-member are cut away to form a recess for the lock casing.

In the normal position of the lock, the bolt 7 is extended outwardly under the action of the spring 11, and the rod 19 is likewise drawn forwardly with its rear end at the forward end of the slotted lever arm 18. In this position, the bolt and rod are free to slide in both directions without moving the inside handle, as would take place when the door is slammed closed or opened from the outside. Similarly, to open the door from the inside, the handle 13 is turned in a clockwise direction (Figure 1), that is, toward the lock casing 6, the rod 19 being shifted endwise to retract the bolt and thus release it

from its keeper. It will be noted that the direction in which the inside operating lever is rotated is opposed to the direction of movement of the bolt due to the intermediate gear sectors. Hence a forward push on the inside handle withdraws the bolt and permits the door to be opened.

I claim as my invention:

1. An extension door lock comprising a lock casing having a bolt mounted on the door frame adjacent one edge, a plate fixed to the door frame remote from said lock casing, a handle-operated shaft journalled on said plate, a gear sector mounted on said shaft, a complementary gear sector journalled on said plate and meshing with said first-mentioned gear sector, said complementary gear sector having a slot therein of a length equal to the throw of said bolt, a rod connected at one end with said bolt and having sliding connection at its opposite end with the slot of said gear sector, one of said gear sectors having an oversized tooth adapted to engage the teeth of the other gear sector to limit the turning movement of said handle in one direction.

2. An extension door lock comprising a lock casing having a bolt mounted on the door frame adjacent one edge, a plate fixed to the door frame remote from said lock casing, a handle-operated shaft journalled on said plate, a gear sector mounted on said shaft, a complementary gear sector journalled on said plate and meshing with said first-mentioned gear sector, said complementary gear sector having a slot therein of a length equal to the throw of said bolt, a rod connected at one end with said bolt and having sliding connection at its opposite end with the slot of said gear sector, said gear sectors having oversized teeth adapted to engage each other at the end of the return movement of said handle from bolt-operating position to lock the parts from further movement in the same direction.

Signed at Chicago, Ill., this tenth day of December, 1928.

AUGIE L. HANSEN.
